HYDRAULIC CRANE UNIT

Glenn J. Wicke and Robert M. Anrig, Ottawa, Kans., assignors to H. & M. Manufacturing Co., Inc., Ottawa, Kans., a corporation of Kansas

Application March 18, 1957, Serial No. 45,300

Term of patent 7 years

(Cl. D41—1)

Fig. 1 is a side view of a hydraulic crane unit embodying our design.

Fig. 2 is a top plan view thereof.

Fig. 3 is a view taken on the side opposite to that shown in Fig. 1.

Fig. 4 is a front view thereof.

Fig. 5 is a rear view thereof.

We claim:

The ornamental design for a hydraulic crane unit, as shown.
